UNITED STATES PATENT OFFICE

2,450,065

DRILLING MACHINE

Herbert J. Willmott, Beverly, Mass., assignor to
United Shoe Machinery Corporation, Flemington, N. J., a corporation of New Jersey

Original application August 4, 1943, Serial No. 497,415. Divided and this application December 21, 1944, Serial No. 569,121

10 Claims. (Cl. 144—93)

1

My invention relates to machines for drilling work of various kinds, it being herein disclosed as applied to the purpose of producing simultaneously a plurality of passages in a wood heel held in place in the machine for the operation upon it. The present case is a division of the application filed in my name in the United States Patent Office on August 4, 1943, and bearing the Serial No. 497,415, this having on July 10, 1945, matured into Patent No. 2,379,944. The invention has as an object the provision of efficient means for actuating, adjusting and determining the adjusted position of the drill or drills.

With the above object in view, a feature of the invention may be found in means by which a drill-mounting is reciprocated to obtain the effect of the drills upon the work in its holder. An oscillatory lever is held against a rotatable cam by a spring, which forces the drill-mounting away from the work-holder. A reciprocatory carrier connected to the lever, as by a pair of links, has spaced abutment-portions between which the mounting extends and with one of which it contacts. A second spring engages one of the abutment-portions of the carrier and also the mounting, it being effective by its expansion to move the mounting toward the holder to cause the drills to enter the work. There results a compact organization by which the drills are yieldably advanced by an unvarying force and retracted at an unvarying rate, regardless of the depth of drilling. The advancing force may, however, be adjusted to meet the requirements of different kinds of work by varying the distance between the elements engaged by the second spring.

As another feature of my invention, the depth of drilling is determined by the operator through means for readily and accurately varying the position of the drill-mounting with respect to the work-holder. A reciprocatory slide has movable upon it a secondary slide carrying the mounting, and a rod rotatable in the second slide is threaded into the first and extends to the front of the machine, where it has a handle adjacent to the work-holder. By turning this rod, and by virtue of its engagement with the two slides, the position of the second slide upon the first and, therefore, the normal relation of the drills to the work-holder, may be altered quickly and with little effort, to give the depth of drilling desired by the operator. Associated with the rod, where it may be observed readily, is means for showing the depth of drilling, as by a nut threaded upon the rod and movable along indicating means, and, to render the reading easy,

2

the indicating movement is multiplied, the two threads upon the rod being reversed in direction.

As still another feature of the invention, there is means by which the secondary or mounting-carrying slide is securely locked in whatever position it may be adjusted. In ways in which this slide is adjustable is a space, in which a block or other member is movable into locking engagement with the slide. Means, as a spring, applies to the block a locking force which is independent of effort on the part of the operator, the action of the spring upon the block being through a lever, preferably of the toggle-type, which multiplies its effect. There is shown means for adjusting the effective pressure-angle of the toggle-lever. Means extending to the front of the machine, adjacent to the means through which the slide is moved, serves to release the slide-locking engagement, and may consist of a rod connected to the lever and acting to break the toggle against the force of the spring.

In the accompanying drawings illustrating a possible embodiment of the invention,

Fig. 1 illustrates my improved drilling machine in side elevation;

Fig. 2 is a top plan view of the means for setting and clamping the drilling head;

Fig. 3, a vertical sectional detail on the line III—III of Fig. 2;

Fig. 4, an enlarged top plan view of the outer end of the adjusting means for the depth of drilling;

Fig. 5, a horizontal sectional detail through the locking means for the depth-adjusting scale; and

Fig. 6, an enlarged broken sectional detail on the line VI—VI of Fig. 1, illustrating the yieldable reciprocating connection for the drill-slide.

The machine comprises more essentially chuck mechanism A, by which a plurality of drills for operating upon heels may be held in individual chucks K and adjusted to different positions to give arrangements corresponding to a particular design in which nails have been inserted in the heel-seat of a shoe to which the drilled heel is to be attached; driving mechanism B by which the drills are rotated through flexible and extensible connections X permitting drill-adjustment; clutch, cam and fan mechanism C interposed between the motor or other source of power and the drill-driving mechanism; and clamping mechanism D with its actuating connections by which the heels are held for the drilling operation.

Upon spaced rods 50, 50, fixed horizontally from front to rear in the upper portion of the frame

52 of the machine, a main drill-actuating slide 54 is movable and has supported upon it a mounting head 56 for the drill-chucks K. To the slide is imparted a reciprocation of unvarying extent to cause drills 58, held in the chucks, to operate upon the work. A cam 60, rotatable by the mechanism C once during each operating cycle of the machine, by contact with a roll 61 rotatable on a bell-crank-lever 62 fulcrumed at 64 upon the mechanism C, oscillates said lever. A roll 66 upon the lever 62 engages the closed end of a thimble 68, movable through a bore in a lug 70 depending from the slide 54. A spring 72 is seated in the thimble 68 with its opposite extremity in an externally threaded thimble 74, adjustable through 10 an opening in the frame. By turning a nut 75 upon the thimble 74, there may be varied the force with which the spring urges a flange 76 upon the thimble 68 against the lug 70, and holds the slide 54 in its normal position with the drills retracted. This position is determined by the contour of the cam 60, in engagement with which the roll 61 is maintained by the spring. Between a lug 78 depending from the slide and a sleeve 80 sliding in the frame, a spring 82 is interposed. This last-mentioned spring is of such strength that it will resist the force necessary to advance the drill-slide 54 for the production of the deepest openings to be formed in the work. It is under constant compression, its force being adjustable by rotation of a screw 84 threaded into the sleeve and against which the outer end of the spring abuts. The expansive force of this loaded spring 82 maintains the lug 78 of the slide in contact with a horizontal crossbar 86, bridged between a pair of links 88, 88 pivoted to the upper end of the lever 62. At their rear extremities, these links are joined at 90, 90 to the sleeve 80. The crossbar, the links and the sleeve move at all times with the lever and may be considered to be a portion thereof. They furnish a carrier for the spring 82. As the cam 60 oscillates the lever 62, its action upon the thimble 68 compresses the spring 72. This movement of the lever-portion 86 in a direction away from the lug 78 permits the spring 82, by its engagement with the lug, to move the slide 54 forward, so the drills 58 act upon the work. If any obstruction is encountered by the drills or slide which offers a resistance greater than the maximum drilling force, it merely causes the compression of the spring 82, and no injury to the elements of the machine will result. When the lever 62 is allowed by the cam 60 to be swung back by the expansion of the spring 72, the slide 54 is retracted by the contact of the flange 76 with the lug 70 at a rate determined by the contour of the cam. This, and withdrawal of the drills from the work, will be rapid, so heating by idle rotation of said drills within the work is minimized. The time of withdrawal may be a relatively small fraction of that required for the operating advance. Since the lug 78 and crossbar 86 and the screw 84, which furnish the abutments for the opposite ends of the spring 82 move together with the lever 62, the resistance to compression of said spring is unaffected by the depth of drilling. The action of the drills is therefore more uniform, and both the springs 72 and 82 may be of less strength than if the screw 84 were a normally fixed abutment. Since the operating force is applied to the drills through the spring 82 and they are retracted by the spring 72, their movement in both directions is cushioned and all shocks absorbed to give smooth reciprocation of the main slide 54.

To provide for drilling heels to different depths, the position of the mounting head 56 upon the main slide 54 is variable. For this purpose, the mounting is fast upon an intermediate or secondary slide 92 movable in ways 94 upon the main slide. The connection of the mounting to the slide 92 may be by screws 95, which pass with some clearance through openings in the connected elements. Thus is furnished a transverse setting-up adjustment for the drills 58. At the underside of the secondary slide is a lug 96, in which turns a rod 98 having collars 100, 100 fixed to it at opposite sides of the lug, and threaded into the main slide at 102, this thread being right-hand. When the rod is turned by a hand-wheel 104 upon its forward extremity, the secondary slide and the mounting 56 with the drills are adjusted to different initial distances from the work, so the unvaried travel of the main slide will carry the drills into the work to a greater or less extent. The hand-wheel is at the front of the machine, convenient for manipulation by the operator as he supplies to the clamping mechanism D the heels to be drilled. In its adjusted position, 20 the secondary slide is locked by engagement of a block 106, movable upon the main slide 54 through a space at one side of the ways 94 and forced against the secondary slide. This movement of the block is effected by a toggle-lever, one link 108 of which is pivoted to it at 110, the other link 112 being pivoted to the first and also to the main slide at 114. The pivot 114 is furnished by an eccentric, which may be rotated to different positions, and is secured by a screw 116. This, 25 to facilitate setting up the machine and to take up wear, permits the establishment between the links of the toggle-lever of an angle giving the maximum or desired efficiency, when the block is in locking engagement with the secondary slide. 30 The center of the toggle is forced toward an adjustable stop-screw 118 into locking relation by an expansion-spring 120 surrounding a rod 122 pivoted to an arm 124 extending from the toggle-link 108 above the link 112. This locking action 35 is entirely independent of effort on the part of the operator and therefore is uniform. The spring is interposed between a bracket 126 projecting from the main slide and a shoulder 128 upon the rod. To unlock the slide 92 for adjustment, the 40 rod 122 is drawn out by a handle 130 at the front of the machine adjacent to the hand-wheel 104, breaking the toggle and withdrawing the block 106 from its locking position, to which it has been urged by the spring 120. With the secondary slide 45 thus freed, the mounting head 56 and the drills may be moved to the desired positions by rotation of the hand-wheel. Unless the rod 122 is drawn out while the adjustment is being made, the secondary slide is at all times held locked ready for 50 the drilling operation. As the block 106 thus secures the secondary slide, it forces said slide against the opposite side of the ways 94. In so doing, it takes up all lateral play and maintains the drills 58 in the correct relation to the clamping mechanism C for all depth-of-drilling adjustments.

To guide the operator in making the adjustment of the drills, there projects from the main slide 54 through an opening in the frame about the rod 98, a tube 132 terminating adjacent to the hand-wheel 104. The tube is cut away along its upper side, and its edge is graduated at 134 in fractions of an inch. Guided in the tube along the graduated opening is an elongated nut 136 55 engaging the rod 98 by a left-hand thread, the

reverse of that between the rod and the slide 54. A projection 138 from the nut into a longitudinal groove 140 in the tube prevents the rotation of said nut. As the rod 98 is turned to produce the adjustment of the slide 92 and the drill-mounting 56 on the main slide, the forward extremity of the nut travels along the scale, indicating the depth of drilling for any setting. The reverse threading of the rod into the nut and the slide multiplies the indicating travel of the nut, so the scale may have longer gradations and be more easily read. To allow an adjustment of the zero position of this gaging device, the tube 132 is clamped in the main slide 54, with a capacity for longitudinal adjustment, by a wedge 142. The wedge is guided in said main slide and bears against the tube. It is forced into locking engagement with said tube by a screw 144 threaded into the wedge and rotatable in the slide 54.

In the use of the machine, a heel to be drilled is applied to the clamping mechanism D. If the drilling design is to be altered from that of the previous operation, the arrangement of the drill-chucks K is changed by the mechanism A. If the depth to which the drills 58 are to penetrate the heel is also to be altered, the operator actuates the rod 122, relieving the toggle-lever 108, 112 of the pressure of the spring 120, thus freeing the secondary slide 92 from the locking action of the block 106. The hand-wheel 104 is then turned until the reading furnished by the relation between the nut 136 and the scale 134 shows that the movement of the drills by the main slide 56 will carry them to the desired depth in the clamped heel. Then, the rod is released to secure the secondary slide upon the main slide under the force of the spring 120. To whatever point the slide has been adjusted, the pressure of the locking block 106 holds it in the true position in its ways, without the possibility of lateral play. Now, by depression of a treadle 362, the clutch mechanism C and driving mechanism B are put into operation for a single cycle, to rotate the chucks K and their drills 58, and to turn the cam 60 to oscillate the lever 62 and reciprocate the main slide with the adjusted drills. The drills are caused to penetrate the heel wholly under the expansive force of the loaded spring 82, this being sufficient to effect the operation to the chosen depth, but providing for yield if an obstruction is encountered. After the advance of the drills has been completed, they are withdrawn from the heel under the force of the spring 72 and at a rate determined by the contour of the cam 60, the speed of movement being such as to prevent overheating during the idle travel of the drills in the heel. The drilled heel may now be removed from the clamping mechanism.

Having described my invention, what I claim as new and desire to secure by Letters Patent of the United States is:

1. In a drilling machine, a frame, a member slidable in the frame, a spring interposed between the frame and member, a lever against which the member is urged by the spring, a rotatable cam against which the lever is held by said spring, a sleeve guided in the frame, links joining the sleeve to the lever, a crossbar connecting the links, a drill-mounting movable upon the frame and having a portion engaging the crossbar, and a spring interposed between the sleeve and mounting-portion and acting to urge said mounting-portion against the crossbar.

2. In a drilling machine, a frame, a drill-mounting movable upon the frame, a thimble

variable in position in the frame, a thimble slideable in the drill-mounting, a spring interposed between the thimbles and by which the slideable thimble is urged into actuating engagement with the mounting, a lever against which the slideable thimble is urged by the spring, a rotatable cam against which the lever is held by said spring, a sleeve guided in the frame, a screw threaded into the outer end of the sleeve, links joining the sleeve to the lever, a crossbar connecting the links and engaged by the mounting, and a spring interposed between the sleeve and mounting and acting to urge said mounting against the crossbar.

3. In a drilling machine, a work-holder, a slide movable toward and from the work-holder, means for reciprocating the slide, a second slide movable upon the first, a mounting carried by the second slide for the reception of drills to act upon the work in the holder, a rod rotatable in the second slide and threaded into the first slide, said rod extending to the front of the machine at the work-holder and being provided with a handle by which it may be turned to vary the position of the second slide upon the first and the relation of the drills to the work-holder, and means surrounding the rod adjacent to the handle and movable along said rod as the distance between the second slide and the work-holder is varied to indicate the depth of drilling.

4. In a drilling machine, a work-holder, a slide movable toward and from the work-holder, means for reciprocating the slide, a second slide movable upon the first, a mounting carried by the second slide for the reception of drills to act upon the work in the holder, a rod rotatable in the second slide and threaded into the first slide, said rod extending to the front of the machine at the work-holder and being provided with a handle by which it may be turned to vary the position of the second slide upon the first and the relation of the drills to the work-holder, the rod being threaded adjacent to the handle, a tube projecting forwardly from the first slide and surrounding the rod, and a non-rotatable nut movable longitudinally within the tube and engaging the thread at the handle, the nut and tube having co-operating means indicating the depth to which the drills will enter the work in the holder.

5. In a drilling machine, a work-holder, a slide movable toward and from the work-holder, means for reciprocating the slide, a second slide movable upon the first, a mounting carried by the second slide for the reception of drills to act upon the work in the holder, a rod rotatable in the second slide and threaded into the first slide, said rod extending to the front of the machine at the work-holder and being provided with a handle by which it may be turned to vary the position of the second slide upon the first and the relation of the drills to the work-holder, the rod adjacent to the handle having upon it a thread which is the reverse of that between the rod and the second slide, a tube projecting forwardly from the first slide and surrounding the rod, and a non-rotatable nut movable longitudinally within the tube and engaging the thread at the handle, the nut and tube having co-operating means indicating the depth to which the drills will enter the work in the holder.

6. In a drilling machine, a work-holder, a slide movable toward and from the work-holder, means for reciprocating the slide, a second slide movable upon the first, a mounting carried by the second slide for the reception of drills to act upon the work in the holder, a rod rotatable in the second

slide and threaded into the first slide; said rod extending to the front of the machine at the work-holder and being provided with a handle by which it may be turned to vary the position of the second slide upon the first and the relation of the drills to the work-holder, the rod being threaded adjacent to the handle; a tube projecting forwardly from the first slide and surrounding the rod, a non-rotatable nut movable longitudinally within the tube and engaging the thread at the handle, the nut and tube having co-operating means indicating the depth to which the drills will enter the work in the holder, and means to clamp the tube in the second slide in different positions along the rod to vary the relation of the portions of the indicating means upon the tube and nut.

7. In a drilling machine, a work-holder, a slide movable toward and from the work-holder and provided with ways in which is a space, means for reciprocating the slide, a second slide variable in position in the ways, a drill-mounting carried by the second slide to act upon work in the holder, means extending to the front of the machine at the work-holder for moving the second slide upon the first to vary the relation of the drills to said work-holder, a member movable in the space in the ways for locking engagement with the second slide, means for creating a locking force, means for applying to the member the locking force thus created, and means extending to the front of the machine adjacent to the slide-moving means for releasing the slide-locking engagement of the member by counteracting the locking force.

8. In a drilling machine, a work-holder, a slide 35 movable toward and from the work-holder and provided with ways in which is a space, means for reciprocating the slide, a second slide variable in position in the ways, a drill-mounting carried by the second slide to act upon work in the holder, 40 means for moving the second slide upon the first to vary the relation of the drills to said holder, a block movable in the space in the ways for locking engagement with the second slide, a lever pivoted to the first slide and to the block, a spring acting upon the lever to force the block into locking engagement with the second slide, and means movable by the operator to free the lever from the force of the spring.

9. In a drilling machine, a work-holder, a slide 50 movable toward and from the work-holder and provided with ways in which is a space, means for reciprocating the slide, a second slide variable in position in the ways, a drill-mounting carried by

the second slide to act upon work in the holder, means for moving the second slide upon the first to vary the relation of the drills to said holder, a member guided in the space in the ways for locking engagement with the second slide, a toggle-lever pivoted to the first slide and to the block, a spring acting upon the toggle-lever to force the block into locking engagement with the second slide, and means for varying the position of the pivotal connection of the toggle-lever to the first slide and thereby the effective pressure-angle of said toggle-lever.

10. In a drilling machine, a work-holder, a slide movable toward and from the work-holder and provided with ways in which is a space, means for reciprocating the slide, a second slide variable in position in the ways, a drill-mounting carried by the second slide to act upon work in the holder, means for moving the second slide upon the first to vary the relation of the drills to said holder, a block guided in the space in the ways for locking engagement with the second slide, a toggle-lever pivoted to the first slide and to the block, a rod connected to an arm of the lever and extending to the front of the machine at the work-holder, and a spring interposed between the rod and the first slide and acting to straighten the toggle-lever and force the block toward the second slide.
